UNITED STATES PATENT OFFICE

150,734

DESIGN FOR A COFFEE MILL

Richard L. Schuhmann, Louisville, Ky., assignor to American Duplex Company, Louisville, Ky., a corporation of Kentucky

Application November 6, 1946, Serial No. 134,551

Term of patent 3½ years

(Cl. D55—1)

To all whom it may concern:

Be it known that I, Richard L. Schuhmann, a citizen of the United States, residing at Louisville, in the county of Jefferson and State of Kentucky, have invented a new, original, and ornamental Design for Coffee Mill, of which the following is a specification, reference being had to the accompanying drawings, forming a part thereof.

In th drawings:

Fig. 1 is a front perspective view of a coffee mill showing my new design;

Fig. 2 is a view of the side opposite that shown in Fig. 1;

Fig. 3 is a front elevation thereof; and

Fig. 4 is a section taken through the lower portion of the supporting upright in Fig. 2.

The back side of the mill is a smooth continuation of the top surface extending directly between the curved side edges.

I claim:

The ornamental design for a coffee mill, substantially as shown and described.

RICHARD L. SCHUHMAN.
